Primary Examiner — Elizabeth J Oswecki

(57) **CLAIM**

The ornamental design for a coin bank and valet, as shown and described.

DESCRIPTION

FIG. 1 is a perspective view of a coin bank and valet, in an open position showing my new design;

FIG. 2 is a perspective view of a coin bank and valet, in a closed position;

FIG. 3 is a top plan view thereof;

FIG. 4 is a bottom plan view thereof;

FIG. 5 is a side view thereof, the opposite side view being identical; and,

FIG. 6 is another side view thereof, the opposite side view being identical.
